OSKAR NEISS, OF HAMBURG, GERMANY, ASSIGNOR OF ONE-HALF TO HERMANN BOLLMANN, OF HAMBURG, GERMANY

INDUCTION HEATING APPARATUS

Application filed December 5, 1928, Serial No. 323,810, and in Germany December 7, 1927.

This invention relates to improvements in the generation of heat by the inductive effect produced by a rotary magnetic field in electrical conductors having the form of tubes or passages serving to accommodate the medium to be heated. Such an arrangement may consist of the short circuited armature of an asynchronous motor which is prevented from rotating and is provided with a short circuited winding made up of tubular elements through which the medium to be heated is led. In devices of this kind the power or heating effect has been controlled by varying the leakage between the primary winding and the short circuited winding or that at some other part of the magnetic circuit. To make this possible the body containing the heating elements had to be capable of variation of position relatively to the rotary field, this necessitating the separation of the primary and secondary parts of the apparatus and resulting in an increase of the resistance of the magnetic circuit. Furthermore due to the mechanical stress caused by the magnetic pull acting upon the heating body, such arrangements have proved useless or defective in practice, their electrical efficiency and power factor being low.

The present invention relates to a heating arrangement employing a rotary magnetic field, wherein the defects referred to are eliminated without the requisite adjustability or regulation of the heating effect being impaired. To this end according to the invention the tube or conduit system constituting the secondary winding is embedded in a common closed magnetic circuit with the primary winding. It is also possible to utilize a plurality of rotary fields in conjunction with a single tube system and to regulate the power by adjustment of the phase difference or differences of said fields. Other features of the invention will appear hereinafter.

One embodiment of the invention is illustrated by way of example in the accompanying drawings in which:

Fig. 1 is a perspective view of the device as constructed to employ two rotary fields.

Fig. 2 is a horizontal transverse section 50 thereof.

Fig. 3 is a diagram of the rotary fields.

In the drawings the reference numeral 1 indicates a laminated iron body or core for carrying the magnetic flux, 2 an exciting primary winding connected to the mains, 3 a 55 secondary multi-phase short circuited tube system and 4 a heat insulating medium.

The tube system 3 behaves like the winding of the short circuited rotor of an excited multi-phase motor which is stationary. To eliminate mechanical stresses acting upon the secondary system, factors which would be regarded as being disadvantageous in this respect in the case of a motor are enhanced according to this invention by accommodating the secondary winding 3, serving as a heating winding, in a common iron body 1 together with the primary winding 2. Thus the invention provides for the complete closure of the magnetic circuit, eliminating any air 70 path and thereby avoiding magnetic or mechanical stresses.

If the best or maximum heating effect is to be obtained in the heating winding it is important that said heating winding be arranged in a certain manner in the iron core and in relation to the primary winding, that is how the rotary field intersects the heating winding. The number of slots for the primary winding should be divisible by the 80 number of slots for the secondary winding to give a whole number, i. e., should have a common factor therewith, so that considering either the primary or the secondary winding two slots of the windings are always 85 opposite to each other. In the preferred case the number of slots for the two windings should be equal. Since according to this invention they are accommodated in a common iron body like or contiguous portions of the 90 two windings may be arranged to lie in opposite end portions or branches of one and the same slots. By this arrangement it is possible to eliminate almost completely all bending stresses acting upon the heating 95 tubes.

According to a further feature of the invention the length of the tubular elements of the heating winding 3 is not limited to the length acted upon by the magnetic field; on

the contrary the tubular elements may be lengthened beyond the extent of the active magnetic iron of the body 1. In other words, the radiating surface of the heating winding traversed by the current may be increased not only by increasing the number of the tubular elements but also by lengthening the same. The use of this arrangement in the known devices would render illusory their regulability by adjustment of the heating winding relatively to the rotary field. This feature of the invention has the advantage that the so-called short circuit current strength may thereby be brought in a simple manner to the value appropriate for the power of the primary winding without it being necessary to employ means, whether of an ohmic or inductive character, which are not free from losses.

In heating systems which are very long in relation to the length of the induced portion thereof, it is possible to cause several such rotary magnetic fields to act upon a common secondary system before the individual tubular elements of the heating system are short circuited together. The heating device may thus be extended to any desired length and in the case of a medium to be heated flowing through the heating winding the device may be divided, say, into initial, intermediate and final heaters; alternatively where no increase of the initial potential is desired over the entire length of the heating winding provision may be made of auxiliary heaters which merely have to cover the radiation losses. In this manner it is simply possible to combine individual devices to form groups or units or to attain an increase in output or power without enlarging the heating system.

Regulation of the output may be provided for simply by suitably dimensioning the heating winding and selecting the material therefor, if it is not preferred to effect this by other means such as variation of the leakage, of the number of ampere turns on the primary winding or of the ohmic resistance as in known arrangements. Regulation may also be effected on the following principle. If two separate rotary magnetic fields act upon a common heating system, then the total power transferred to the heating system is a function of the geometrical sums of the two rotary fields so acting. If the sum is zero, that is if there is a phase displacement of 180 electrical degrees between the fields, then the power transferred will also be zero and no heat will be evolved. Thus the heating effect of the heating winding may be infinitely regulated or varied in dependency upon the degree of the phase displacement.

This regulation by control of the phase displacement of several rotary fields relatively to one another has the advantage over known arrangements that there is no necessity for mechanical displacement of the heat-

ing winding relatively to the primary winding or to the rotary field or vice versa but merely for adjustment of the leading or lagging phase of the rotary field which, of course, has no weight. The phase displacement may naturally also be effected by rotation in space of several rotary fields. Even in this case, however, alteration in the magnetic resistance and thus a reduction of the power factor would not be caused, since the relative position of the heating body to the rotary field is invariably the same. The phase displacement may be controlled automatically by a heat sensitive regulating device and may be effected by varying the velocity of the rotary field.

In the specific construction disclosed showing the invention embodied in a device having two rotary fields, 1 and 1^a, respectively, designate the laminated cores or piles of sheet metal of the upper and lower fields, the core 1 being provided with the primary exciting winding 2, arranged in group divisions 2', 2'', 2''', 2', 2'', 2''' in slots therein about the tube system 3 extending through both cores and serving as the secondary winding, the tubes 3 being united at their ends by rings or heads 5 which may or may not serve as intake and return or discharge headers. The lower core 1^a is provided with a primary winding 6 arranged in group divisions 6', 6'', 6''', 6', 6'', 6'''.

Fig. 3 illustrates a diagram in which 2 and 6 represent the rotary fields, 7 represents the zero point, 7, 9 the potential circle, and 7, 8 is the vector sum representing the magnitude of the net effect of the two rotating fields 2 and 6.

The dotted lines and arrows show how the fields *a* and *e* are displaced in both piles. 2', 2'', 2''', 2', 2'', 2''' as shown illustrate the succession of the displaced phases in the upper rotary field *a* (Fig. 1), and 6', 6'', 6''', 6', 6'', 6''' the succession of the displaced phases in the lower rotary field *e*.

The results produced by the alternating current are as follows:

To obtain the maximum heating effect the phases must be parallel in both of the laminated cores, and the alternating current has to move the same way.

The heating effect is equal to naught in case the phases are in parallel in both of the laminated cores and the alternating current moves the opposite way.

The order of succession of the phases shown, i. e., 60° in opposite directions, produces 66 2/3% of the maximum heating effect. To obtain the maximum heating effect of 100% the succession of the phases in rotary field *e* has to be changed as follows: 6', 6'', 6'', 6', 6''', 6''. The latter heating effect corresponds to diameter 7, 9 of the power circle shown in the diagram. To reduce the heating effect to 33 1/3% it is necessary to change

the succession of the phases in the lower rotary field *e* as follows: 6'', 6'', 6', 6'', 6'', 6'.

Apart from the multifarious possibilities of use or applications of such a heating arrangement in the chemical industry for such purposes as producing or dissipating mists and cloud, gasification and heating, it represents an important advance in the steam raising art generally, being applicable with economical results to the production of dry steam and to the bridging of the distance separating producer and consumer and also in particular to the production of high pressure steam.

15 *I claim:*—

1. An induction heating apparatus of the type set forth comprising a plurality of primary windings and a tube or conduit system 20 for containing the medium to be heated and constituting a secondary winding, each primary winding being embedded with the secondary winding in a common closed core, and the secondary winding being prolonged 25 beyond each core, said primary windings presenting a plurality of independent rotary fields in phase displacement to regulate the heating effect.

2. In induction heating apparatus as 30 claimed in claim 1, the disposal of contiguous primary and secondary windings in the same core slot.

3. In induction heating apparatus as 35 claimed in claim 1, the combination of a plurality of separate magnetic rotary fields with a single secondary tube system.

4. In inducting heating apparatus as 40 claimed in claim 1, a plurality of separate rotary fields of varying relative phase arrangement between the separate rotary fields for the purpose of controlling the heating effect.

5. An induction heating apparatus employing a plurality of primary windings and 45 multiphase alternating current for the generation of secondary currents in an electric conductor serving as a secondary winding and arranged as a tube system through which the element to be heated is conducted, said tube 50 system and each primary winding being embedded in a closed iron magnetic core and prolonged beyond it, and said primary windings presenting a plurality of independent rotary fields arranged so that the phases within 55 the individual rotary fields are displaced from one another.

In testimony whereof I affix my signature.
OSKAR NEISS.
